D. E. SPEICHER.
POULTRY HOUSING DEVICE,
APPLICATION FILED NOV. 18, 1918.

1,345,968.

Patented July 6, 1920.

UNITED STATES PATENT OFFICE.

DANIEL E. SPEICHER, OF URBANA, INDIANA, ASSIGNOR TO THE CYCLONE MANUFACTURING COMPANY, OF URBANA, INDIANA.

POULTRY-HOUSING DEVICE.

1,345,968.

Specification of Letters Patent.

Patented July 6, 1920.

Application filed November 18, 1918. Serial No. 263,021.

To all whom it may concern:

Be it known that I, DANIEL E. SPEICHER, a citizen of the United States, residing at Urbana, in the county of Wabash and State 5 of Indiana, have invented certain new and useful Improvements in Poultry-Housing Devices, of which the following is a specification.

This invention relates to improvements 10 in poultry housing devices such as shown and claimed in Letters Patent #1,303,736 issued May 18, 1919, and it is the principal object of the invention to provide the housing device with a novel form of bracing or 15 reinforcing means adapted for arrangement across the normally open end of the main housing section thereof whereby the sides of the section will be maintained in rigid spaced relation and in consequence will permit 20 the parking or secondary section of the device to be freely adjusted with relation thereto and also will permit the housing device to be used with or without the bottom. 25 Another and equally important object of the invention is to provide a novel form of removable bottom for the main section so formed as to provide guides for the lower marginal portions of the secondary section, 30 shifting of said bottom with relation to the main section being prevented by its engagement with the reinforcing element.

Other objects will be in part obvious and in part pointed out hereinafter. 35 The improvements in the details and arrangement of parts will be apparent from an inspection of the accompanying drawings when considered in connection with the specific description hereinafter contained and 40 wherein a preferred embodiment of the invention is shown for the purpose of imparting a full understanding thereof.

In the drawings:

Figure 1 is a perspective view of the improved housing device in its extended position.

Fig. 2 is a vertical longitudinal section therethrough, the removable bottom being shown by full lines in normal lowered position, while by dotted lines the said removable bottom is slightly inclined to disclose the path of movement in removing the bottom from the housing section.

Fig. 3 is a fragmentary end elevation of 55 the main housing section, and

Fig. 4 is a reduced detail in perspective of the novel form of removable flooring employed in connection with the main housing section.

Having more particular reference to the drawings in connection with which like reference characters will designate corresponding parts throughout the several views, 1 represents the main housing section of the device, the lower marginal portions of which 65 are flanged at 2 while the marginal portions thereof adjacent the forward or normally open end of the same are rolled and receive a wire bracing or reinforcing member therein, one portion of said member extending 70 transversely across the lower portion of the open end of the section 1 as indicated by the numeral 3 and being provided with upwardly bent fingers or stops 4, the purpose of which will be presently apparent. To 75 permit the device to be readily carried, a handle 5 of suitable form may be and preferably is engaged with the top portion of the section 1.

Snugly received in the lower portion of 80 the housing section 1 and resting on the flanges 2 formed on the lower ends of the walls thereof is the removable floor 6, which as will be noted is provided with right angularly formed flanges 7, certain of which 85 engage the flanges 2 while the remaining or forward flange is received under that portion of the reinforcing wire indicated by the numeral 3 as clearly shown in the Fig. 3; the fingers or stops 4 serving to positively stay undue movement or shifting of the floor 6 with relation to the section 1, that is, longitudinally of the same. The fingers or stops 4 not only serve to prevent longitudinal movement of the flooring 6 as 90 does the wire from which they are struck or formed, but they also serve to prevent upward or near vertical movement of the opposite end of the flooring such as might be permitted should the flooring be engaged 100 only by the lower portion of the bracing wire. In other words the formation of the fingers or stops 4 in the lower portion of the bracing wire serves to prevent the wire from acting as a pivot upon which the flooring 6 105 could move. In this connection, it is to be noted that the flanges formed on the opposite sides of the floor 6 are of widths such as will cause the body portion of the floor to be spaced inwardly from the adjacent 110

portions of the side walls of the section 1 and in consequence will provide longitudinally disposed parallel ways. The fingers or stops 4 are located on the portion 3 of the reinforcing wire so as to be disposed contiguous to the ways in the floor 6.

10 Telescopically engaged with the main section 1 is a secondary or parking section 8, the sides and top of which are formed of foraminated material having its free marginal portions braced by strips 9 secured thereto. The inner end of the secondary section 8 is open while the outer end thereof is closed by a wall 10 formed with an exit 15 11, which as will be noted, can be closed by doors 12 and 13, the door 13 being of foraminated material and so arranged as to be covered by the adjacent door 12 when desired. Rotatable locking pins 14 are engaged with the wall 10 and are adapted to 20 pass through openings formed in portions of these doors 12 and 13 whereby the same can be positively held in their open or closed positions.

25 To effect ventilation of the housing device when closed, circularly disposed ventilating openings are formed in the upper portions of the end walls of the sections 1 and 8 and receive cutoff plates 15 there-
30 over, these plates being formed with corresponding openings adapted to align, when desired, with said first opening. Hence, by rotating the control plates 15, the size of the openings in the end walls of the sev-
35 eral sections can be controlled and in this way proper ventilation of the device will be insured.

From the foregoing, it will be readily understood by persons skilled in the art that I have provided an exceedingly simple, compact and durable form of housing device for poultry, further, a device which will be found particularly advantageous for use in connection with the raising of chickens. By reason of the engagement of the reinforcing wire with the forward or open end of the main section 1 of the device, the adjacent portions of said section will be materially rigidified and braced and therefore, movement of the parking section 8 into and out thereof can be effected with ease and without liability of binding in the section 1, such as may be caused by the impinging of the side walls on the side walls of this parking or secondary section. Furthermore, distortion or undue movement of the floor 6 such as may be caused by movement of the side walls of the main section 1 will be prevented, while longitudinal shifting of the floor will be prevented by reason of the stops 4 formed on the portion 3 of the reinforcing wire.

Manifestly, the construction shown is capable of considerable modification and

such modification as is within the scope of my claims, I consider within the spirit of my invention. 65

I claim:

1. In a housing device having guide ways at the bottom thereof and an open front, 70 and a bracing element extending around the open front and held fast thereto and having portions contiguous to said ways conforming to the shape thereof.

2. In a telescopic housing device having 75 an opening, a removable floor for the device, and a bracing element extending transversely across the lower portion of the opening and having connection with the sides of said device and overlying a portion of the 80 floor to provide a retainer therefor and to prevent sliding movement of the latter.

3. In a telescopic housing device, a bracing element carried by one of the telescoping sections of said device at the lower portion 85 thereof, a flooring removably arranged in one of said sections and underlying the lower portion of the bracing element to hold said flooring fixed against sliding movement. 90

4. In a telescopic housing device, a flooring arranged in one section thereof having longitudinal ways formed therein for receiving portions of the other section, and a bracing element extending transversely 95 across the lower portion of the open end of said first section and overlying a portion of the flooring to prevent longitudinal movement thereof.

5. A telescopic housing device including 100 main and secondary sections, said main section having the lower portions thereof flanged, a flooring arranged on said flanges, said flanges being formed with longitudinally disposed ways for receiving the lower 105 marginal portions of the secondary section, and a bracing element extending transversely across the lower portion of the open end of said main section having connection with the sides thereof and overlying a portion 110 of the floor.

6. In a housing device having telescoping sections open at their ends interfitted with each other, a bracing element extending 115 transversely across the lower portion of one open end and having connection with the sides of said section, portions of the said bracing element being bent to provide guides for the other telescopic section, and a removable floor arranged in the first named 120 section and having its forward portion bent to engage with the bracing element so as to hold the floor against sliding movement.

7. In a housing device having a body 125 open at its bottom and front, a bracing element secured to the open front and disposed transversely across the open bottom adjacent to said open front, and a flooring re-

movably held in the body to close its open bottom and detachably engaged with the transverse portion of said element.

8. In a housing device having a body open at its bottom and front, a bracing element secured to the open front and disposed transversely across the open bottom adjacent to said open front, and a flooring removably held in the body to close its open bottom and detachably engaged with the transverse portion of said element, and a telescoping section slidable in the body.

9. In a housing device having a body open at its bottom and front, a bracing ele-

ment secured to the open front and disposed transversely across the open bottom adjacent to said open front, and a flooring removably held in the body to close its open bottom and detachably engaged with the transverse portion of said element, and a telescoping section slidable in the body, the sides of the body and the element being constructed and arranged to provide ways for the sliding section.

In testimony whereof, I affix my signature hereto.

DANIEL E. SPEICHER.
